UNITED STATES PATENT OFFICE.

CHARLES S. JOHNSON, OF CHAMPAIGN, ILLINOIS.

BATCH HOPPER.

Application filed March 12, 1926. Serial No. 94,157.

My invention relates to improvements in material storage devices and has particular reference to batch hoppers such as are used in concrete mixing machines and the like.

5 In mixing concrete it has been the practice to introduce all of the ingredients forming the batch into a single hopper for discharge into the mixing drum. Usually the sand, gravel or other aggregate used in making 10 concrete is moist and will so dampen the inner surfaces of the hopper that any powdered cement coming in contact therewith will tend to stick and harden. For this reason, the ingredients will not slide out freely with the 15 result that the proportions of the mix will be changed.

It is the primary object of the present invention to overcome these difficulties by providing an improved batch hopper for concrete mixers having a novel means for preventing the powdered cement from coming in contact with any surfaces which are apt to be dampened by contact with moist sand or other aggregate.

25 Stated more specifically the invention aims to provide a large hopper in which the aggregate for the bath is stored and a smaller cement hopper having an outlet opening within said large hopper, the opening being 30 closed by the aggregate initially fed into the large hopper whereby the cement flowing from the cement hopper will be surrounded by a layer of the aggregate and thereby held out of contact with the inner surface of the 35 large hopper.

Other objects and advantages of the invention will become apparent from the following detailed description taken in connection with the accompanying drawings in which

40 Figure 1 is a fragmentary sectional view of a mixing machine equipped with a batch hopper embodying the features of the present invention.

Fig. 2 is a sectional view taken along the 45 line 2-2 of Figure 1.

Fig. 3 is a fragmentary plan view of the portion of the machine shown in Figure 1.

Figure 4 is a sectional view taken along line 4-4 of Figure 1.

50 Fig. 5 is a fragmentary plan view of a modified form of the invention.

Fig. 6 is a sectional view taken along line 6-6 of Fig. 5.

While I have shown in the drawings and

will herein describe the preferred embodiments of the invention, it is to be understood that I do not intend thereby to be limited to the particular forms disclosed, but aim to cover all modifications and alternative constructions falling within the spirit and scope of the invention as expressed in the appended claims.

Referring to Figures 1 to 3 of the drawings, 55 10 represents the revolving drum of an ordinary concrete mixing machine, and 11 designates generally a hopper for receiving the batch which is to be discharged into the mixing drum. In the present instance, the hopper is stationarily mounted on the frame of 60 the mixing machine, but it will be apparent 65 of the invention as expressed in the appended claims.

70 Referring to Figures 1 to 3 of the drawings, 10 represents the revolving drum of an ordinary concrete mixing machine, and 11 designates generally a hopper for receiving the batch which is to be discharged into the mixing drum. In the present instance, the hopper is stationarily mounted on the frame of 75 the mixing machine, but it will be apparent 80 that the present invention is applicable as well to movable batch hoppers.

85 Preferably the hopper 11 comprises a flat front wall 12 substantially triangular in shape to which is secured a wall 13 of semi-circular cross section. The latter tapers downwardly and terminates at its lower end in a curved trough or spout 14 which projects through an opening in the mixing drum and serves to deliver the ingredients of the batch to the drum. To provide a discharge 90 outlet for the hopper, an opening is cut in the front wall 12 corresponding in shape to that of the trough 14, the flow of materials through this opening being controlled by a valve in the form of a gate 15 pivoted at its upper edge on the front wall 12 so as to swing outwardly.

95 As a suitable means for manually moving the gate into open and closed position, a bell-crank 16 is mounted to turn on the same axis as the gate, one arm being secured to the gate and the other connected to suitable actuating means such as the rod 17. In the form shown herein the rod is received in a notch or recess 100 formed in a re-enforcing bar 18 on the hopper, and is held in raised and lowered positions by fixed collars 19 and 20 which engage respectively with the upper and lower sides of the bar 18. Thus the gate may be held in closed position against the front wall 12 while the batch is being prepared and may be swung upwardly as shown in Fig. 1 to permit the ingredients to flow into the mixing drum.

105 Mounted within the hopper 11 is a smaller hopper 21 which provides a cement compartment, and divides the large hopper into two

compartments, one for the fine aggregate and the other for the coarse aggregate. Preferably the discharge opening of this hopper is of substantially less width than the outlet of the aggregate hopper and is disposed within the aggregate hopper so as to be closed by the sand or gravel initially introduced. To these ends, the cement hopper shown herein comprises two spaced parallel plates 22 secured at their forward edges to the front wall 12 and having their rear edges connected by an inclined plate 23 fastened at its upper end to the edge of the aggregate hopper. The plate 23 and the wall 13 diverge downwardly, and the latter is cut off at a substantial distance from the front wall 12 to provide a cement outlet of considerable length. The side edges of the cement outlet are also spaced from the inner surfaces of the hopper wall 13 by cutting away the lower edges of the side plates 22 as indicated in Fig. 1.

Rearwardly projecting portions 24 of the side plates are positioned relatively close to the inner surface of the wall 13 thereby serving to keep the aggregate from flowing inwardly at a point above the forward edge of the cement hopper outlet to choke the cement flow therefrom. In the present instance, the front edge of the cement hopper outlet coincides with the upper edge of the outlet from the hopper 11, but all of the other edges of the cement hopper outlet are spaced a substantial distance from the inner surface of the aggregate hopper.

In preparing a batch of materials in the present device, the gate 15 is first closed and the sand and crushed rock, or other aggregate, are introduced into their respective compartments. These will slide down the inner surface of the hopper 11 completely closing the outlet of the cement hopper and filling the space between the outer surface of the cement hopper and the inner surface of the aggregate hopper. The cement is then introduced into its hopper. When the gate is opened to release the aggregate, the cement will be released by the sliding of the aggregate downwardly and will flow out of its hopper in a stream equal in width to the distance between the side plates 22, this stream being enveloped by a layer of aggregate as shown in Fig. 4. While the hoppers are thus being emptied, the aggregate in the space about the cement outlet will slide downwardly thereby maintaining a layer of aggregate on the inner surface of the wall 13 beneath the cement outlet. Since the cement outlet is made relatively large and since more aggregate than cement is used in ordinary concrete mixes, it is apparent that all of the cement will have passed out before the supply of aggregate in the outer hopper is exhausted. Thus by maintaining a supply of aggregate around the cement hopper until all of the ce-

ment has been discharged, contact between the cement and the inner surface of the aggregate hopper is effectually prevented. Another advantage of the present arrangement is that the cement and aggregate will be fed into the mixer simultaneously. Mixing will therefore start immediately.

In the modified form of the invention shown in Figs. 5 and 6, only one aggregate compartment is provided. In this arrangement the cement hopper is positioned against the front wall 12 of the aggregate hopper. As in the form previously described, the outlet of the cement hopper is positioned adjacent the outlet of the aggregate hopper and is arranged to discharge a layer of cement onto the stream of aggregate flowing out of the aggregate hopper. This arrangement is particularly useful where gravel or mixed aggregate are used.

I claim as my invention:

1. A batch hopper for concrete mixing machines comprising, in combination, a hopper for containing the aggregate having a tapering body portion and a discharge outlet, a gate arranged to control the flow of materials from said outlet, a cement hopper having a tapering body portion the lower end of which defines an opening narrower than said outlet, said cement hopper being mounted in said aggregate hopper and having its lower rear and lower side portions supported a substantial distance from the bottom and side portions of said aggregate hopper.

2. A device of the character described, comprising in combination, a hopper providing a compartment having an outlet near its lower end, a gate controlling the flow of material from said outlet, a second hopper having a discharge outlet within said first mentioned hopper and adjacent the outlet thereof, the width of said inner hopper outlet being substantially less than the width of said outer hopper at the point of discharge of said inner hopper, and the rear discharge edge of said inner hopper being a substantial distance above the bottom of said outer hopper.

3. A batch hopper for concrete mixing machines comprising, in combination, a hopper for containing the aggregate for a batch having an outlet at its lower end, the body portion of said hopper being shaped to discharge a stream of aggregate through said outlet, a cement hopper arranged to discharge a layer of cement upon the stream of aggregate flowing from said outlet, the width of said cement layer being substantially less than that of said outlet.

4. A device of the character described, comprising, in combination, a hopper providing a material compartment having an outlet opening, the walls of said compartment being adapted to direct the flow of material through said opening, means for open-

ing and closing said outlet opening, and means providing a second compartment having an outlet disposed within said first mentioned compartment and adapted to be closed by the material contained therein.

5. A device of the character described having two compartments, one having a valve controlled outlet and the other having an outlet opening disposed within the first compartment and arranged to be closed by the material contained in said first mentioned compartment.

10. A batch hopper for concrete mixing machines comprising, a hopper for containing the aggregate for the batch, said hopper having a gate controlled outlet, and a cement hopper having an outlet opening disposed within said first mentioned hopper and adapted to be closed by the aggregate initially fed into said first mentioned hopper.

15. A device of the character described comprising, in combination, a hopper having a downwardly tapering body portion open at its lower end, and a second hopper having a tapering body portion providing a storage compartment surrounding the body portion

of said first mentioned hopper, said second hopper having a valve-controlled outlet.

20. A batch hopper for concrete mixing machines comprising in combination, a downwardly tapering hopper having a discharge spout at its lower end and an outlet opening above said spout, means for controlling the flow of material from said opening, and a cement hopper having an outlet opening 35 within said first mentioned hopper, the forward edges of said cement hopper outlet being disposed substantially in the plane of the upper edge of said first mentioned outlet.

25. The combination of two hoppers, one 40 adapted to contain the aggregate and the other the cement for a concrete mix, said hoppers being arranged so that in the discharge of the aggregate and cement from their respective hoppers the aggregate serves to 45 envelope the cement to prevent the latter from coming into contact with surfaces engaged by the aggregate.

In testimony whereof, I have hereunto affixed my signature.

CHARLES S. JOHNSON.
